DESIGN FOR A REFRIGERATOR CABINET

Paul M. Koons, Muncie, Ind., assignor to Glascock
Brothers Mfg. Co., Muncie, Ind., a corporation
of Indiana

Application July 1, 1936, Serial No. 63,593

Term of patent 7 years

To all whom it may concern:

Be it known that I, Paul M. Koons, a citizen of the United States, residing at Muncie, in the county of Delaware and State of Indiana, have invented a new, original, and ornamental Design for a Refrigerator Cabinet, of which the following is a specification, reference being had to the accompanying drawing, forming part thereof.

The figure is a perspective view of a refrigerator cabinet embodying my design, the side and

end not shown in the illustration being the same as the side and end shown.

I claim:

The ornamental design for a refrigerator cabinet, as shown and described.

In witness whereof, I have hereunto set my hand at Muncie, Indiana, this 27th day of June, A. D. one thousand nine hundred and thirty six.

PAUL M. KOONS.
